UNITED STATES PATENT OFFICE.

ERNEST A. MEYER, OF FREEPORT, PENNSYLVANIA.

TWO-CYCLE INTERNAL-COMBUSTION ENGINE.

956,814.

Specification of Letters Patent.

Patented May 3, 1910.

Application filed March 22, 1909. Serial No. 485,018.

To all whom it may concern:

Be it known that I, ERNEST A. MEYER, citizen of the United States, residing at Freeport, in the county of Armstrong and State of Pennsylvania, have invented certain new and useful Improvements in Two-Cycle Internal-Combustion Engines; and I do hereby declare the following to be a full, clear, and exact description of the invention, such as will enable others skilled in the art to which it appertains to make and use the same.

My invention relates to explosive or internal combustion engines of the two cycle type and consists in the novel features hereinafter described reference being had to the accompanying drawings which illustrate two forms in which I have contemplated embodying my invention and the invention is fully disclosed in the following description and claims.

In the drawings which illustrate my invention applied to a two cylinder engine, Figure 1 represents a vertical transverse section of the engine taken through one of the cylinders, and showing the pistons at the end of the inward stroke. Fig. 2 is a similar view showing the piston at the end of the explosion or outward stroke. Fig. 3 is a vertical longitudinal sectional view of the engine, with part of the crank case broken away and one cylinder removed. Fig. 4 (Sheet 1) is a bottom plan view of the stationary piston or casing hereinafter referred to. Fig. 5 (Sheet 2) is a top plan view of the same. Fig. 6 is a sectional view similar to Fig. 1 showing a modification of the invention.

As stated, I have illustrated my invention as applied to a two cylinder engine, but as each cylinder is independent of the other or others, in operation, a description of the construction and operation of a single cylinder will be sufficient, and it will be understood that one or any desired number of cylinders may be employed, as desired, by arranging the cranks on the crank shaft in such manner as to secure the desired balancing of the engine when in operation.

According to my invention the engine cylinder is formed with two co-axial parts of different diameters and the moving piston

is constructed with co-axial portions of different diameters to engage the same, and is further provided with an internal cylinder or trunk which is engaged by a stationary piston.

In the drawings, Figs. 1 to 5 inclusive, 1 represents the smaller diameter of the cylinder constituting the explosion chamber and 2 represents the larger diameter of the cylinder constituting the outer wall of the compression chamber or pump co-axial therewith. 3 represents the portion of the moving piston of smaller diameter working in the explosion chamber 1, and 4 represents the larger portion of the moving piston working in the pump chamber 2. The piston is hollow and the lower portion is turned as at 5 so as to form an interior cylindrical portion which fits over the stationary piston or sleeve 6, the outer wall of which forms the inner wall of the pump chamber, which as will be seen, is annular in form. The stationary piston 6 is provided with a central aperture 7, for the passage therethrough of the connecting rod 8, and the walls of the stationary piston are cored out to form a chamber 9, which is in communication with two segmental shaped apertures 10, 10 at its lower end, and with a series of openings or ports 11, 11 in the outer wall adjacent to its upper end. The lower end of the stationary piston is preferably provided with an outwardly projecting flange 12, which is supported by the crank case, and extends outwardly to the wall of the larger diameter of the cylinder the latter being also supported on the crank case. The explosion chamber 1 at the inner end of the moving piston, is provided with the usual water jacket 13, and igniter 14, and also has its wall provided with a fuel inlet port 15, and an exhaust port 16, preferably located opposite the inlet port and so arranged that it will be opened by the working stroke of the piston, slightly in advance of the fuel inlet port. The piston is provided with a deflector portion 17, at the part which is adjacent to the inlet port when the piston is at the end of its out stroke to deflect the incoming charge toward the upper end of the cylinder. The cylinder structure is provided on the side adjacent to the inlet port 15, with an exterior

wall 18, forming a charge transferring chamber 19, in communication with the inlet port, and a charge transferring passage 20 communicating at its upper end with the chamber 19 and at its lower end with an outlet port 21, which I term the transfer port opening into the pump chamber at the lower end of the same. The crank case is preferably formed in two sections although it 10 may be formed in one or more sections as desired. The upper part of the crank case, here indicated at 22, is provided with a flat top face to receive the cylinders and the stationary pistons or sleeves, as before described, the crank case being shown in Fig. 2 as arranged to accommodate two cylinders of the kind previously described. The upper part of the crank case is provided with apertures 23, 23 to accommodate the movements of the connecting rods 8, and is cored out around the said apertures as shown in Figs. 1, 2 and 3 to provide a chamber 24 which is separated entirely from the interior of the crank case, so that no oil can be 25 thrown into said chamber from the crank case. The upper face of the crank case is provided adjacent to each cylinder with segmental shaped apertures 25, 25 which register with the apertures 10, 10 in the stationary pistons (see Fig. 3) or sleeves, and thus place the crank case chamber 24 in communication with the chambers 9, 9 in the walls of the stationary pistons. The lower part 26 of the crank case is closed and forms a receptacle for oil to lubricate the connections between the connecting rods 31, 31 of the crank shaft 30, the latter being mounted in suitable bearings 32 in the ends of the crank case, one of which bearings is shown in 40 Fig. 3.

In the form of engine illustrated in Figs. 1, 2 and 3, the explosive mixture is introduced into the crank case chamber 24, the crank case being provided on opposite sides with 45 openings 27, 27, one of which is closed as by a plate 28, and the other connected with a pipe 29, leading from a carburetor or other supply of explosive mixture, or fuel.

The operation of the engine will be described with reference to a single cylinder, it being understood that the cycle of operations is the same in each cylinder where more than one is employed. As the piston moves inwardly toward the extreme position which 55 is illustrated in Fig. 1, a previously admitted charge is compressed in the explosion chamber 1, and a partial vacuum is created in the compression or pump chamber 2, until the port or ports 11 in the stationary piston or 60 sleeve is or are uncovered, when a charge of fuel rushes into the compression chamber 2. The previous charge in the explosion chamber is then ignited and the piston moves outwardly for its working stroke, the pump

portion of the piston closing ports 11 and 65 compressing the fresh charge in the compression chamber 2, and forcing it out through the transfer port 21, into the transfer passage 20, and chamber 19. As the piston moves outwardly, the portion 3 of 70 smaller diameter uncovers partially the exhaust port 16, permitting a partial escape of the exploded or burned gases, and then uncovers the inlet port and fully uncovers the outlet port, permitting the compressed fresh 75 charge to rush into the inlet port, where it is deflected by deflector 17, toward the head of the cylinder, and sweeps out the burned gases. The next inward stroke of the piston causes the portion of the piston of smaller 80 diameter to close first the inlet port and then the exhaust port and recompress the fresh charge, another fresh charge being drawn into the compression chamber 2 as previously described. The compressed charge in 85 the explosion chamber is then ignited, and the operations follow in the cycle above set forth, there being an explosion at the end of each inward stroke of the piston.

In order to prevent the alternate compression and expansion of air on the outer or upper side of the portion of the piston of larger diameter the portion 2 of the cylinder of larger diameter is provided with what I term a breathing aperture 2^a communicating 95 with the atmosphere.

In Fig. 6 I have shown a modification of my engine in which the explosive mixture or fuel is admitted directly to the transfer passage instead of being admitted through the 100 crank case chamber. In this figure 101 represents the explosion chamber, 102 the compression chamber, 103 the portion of the piston of smaller diameter and 104 the portion of larger diameter, 106 the stationary 105 piston and 122-126 the crank case, all constructed substantially as previously described except for certain details which I will now point out. The transfer chamber 119 is preferably provided with a partition 110 119^a in line with the inner wall of the transfer passage 120, and an aperture 119^b in the outer wall adjacent to the top of said portion which is connected by a pipe 129 with the carburetor or other source of explosive fluid 115 or mixture. The inlet pipe or passage 129 is also provided with a check valve 129^a which permits the ingress only of the explosive material or fuel. Air only is drawn in (if at all) through the crank case chamber 124 and the walls of the stationary piston, and I may provide an additional air inlet port 124^a for admitting air to the compression chamber as hereinafter described. Where the port 124^a is provided, I may close 125 both apertures 127 in the crank case, and rely entirely upon the port 124^a for the admission of air if desired.

In the operation of the engine shown in Fig. 6, when working under full load conditions, the charge is drawn in from pipe 129 and down through passage 120 to the pump chamber, on the inward stroke of the piston, and when the ports 11 (and 124^a) are opened no appreciable quantity of air will enter the compression chamber, as it will be filled with the explosive mixture. The charge is compressed and transferred into the passage 120 and chamber 119, as previously described, the check valve 129^a remaining closed during the compression stroke, and the cycle of the engine will be as previously described. If, however, the admission of explosive charge through pipe 129, is partially cut off as by means of a cut off or throttle valve indicated at 129^b, a partial vacuum will be produced in the compression chamber 102 by reason of the explosive mixture not flowing in fast enough to equal the displacement of the pump portion 4 of the piston, and when the ports 111 (and 124^a) are opened, a quantity of air will rush into the compression chamber sufficient to bring the pressure therein up to that of the atmosphere. This air does not at once mix with the explosive mixture and on the compression stroke of the pump portion of the piston, the gas or explosive mixture is forced up around the partition 119^a into the chamber 119, and the air, practically pure, coming last is forced into the top of the transfer chamber, and rushes into the explosion chamber, when the inlet port 115 is opened, ahead of the mixture or gas. This prevents the fresh charge from becoming mixed with the burnt charge, and precludes all possibility of back firing.

What I claim and desire to secure by Letters Patent is:

1. In a two cycle internal combustion engine, the combination with the cylinder provided with co-axial portions of different diameters, a stationary piston within the portion of larger diameter and a moving piston having portions of different diameters working in said co-axial portions of the cylinder and a portion working upon the stationary piston, thereby forming an explosion chamber at the inner end of the piston and a pump chamber at the outer end of the piston, said explosion chamber being provided with a fuel inlet port, and an exhaust port in its lateral walls, opened and closed by the moving piston the pump chamber having an outlet port at its outer end communicating with the inlet port of the explosion chamber, said stationary piston having a central aperture for the connecting rod, a chamber surrounding said aperture, a port at its inner end located in its lateral wall and opened and closed by the pump portion of the moving piston, a crank case adjacent to the outer end of the cylinder and stationary piston,

provided with an aperture for the connecting rod, and having a chambered portion adjacent to said aperture, but separated from the interior of the crank case, said chambered portion having apertures communicating with the chamber in the stationary piston, and an inlet aperture at the exterior of the crank case. 65

2. In a two cycle internal combustion engine, the combination with the cylinder provided with co-axial portions of different diameters, a stationary piston within the portion of larger diameter and a moving piston having portions of different diameters working in said co-axial portions of the cylinder and a portion working upon the stationary piston, thereby forming an explosion chamber at the inner end of the piston and a pump chamber at the outer end of the piston, said explosion chamber being provided with a fuel inlet port, and an exhaust port in its lateral walls, opened and closed by the moving piston, a transfer chamber adjacent to the fuel inlet port and communicating therewith adjacent to one end, said pump chamber having an inlet port at its inner end communicating with the atmosphere and opened and closed by the pump portion of the moving piston, and having an outlet port at its outer end communicating with the transfer chamber by a transfer passage, 85 said transfer passage opening into the transfer chamber at a point adjacent to the fuel inlet port, a passage for admitting fuel to the transfer passage, a check valve for the fuel admission passage and a throttling device for the fuel admission passage. 90

3. In a two cycle internal combustion engine, the combination with the cylinder provided with co-axial portions of different diameters, a stationary piston within the portion of larger diameter and a moving piston having portions of different diameters working in said co-axial portions of the cylinder and a portion working upon the stationary piston, thereby forming an explosion chamber at the inner end of the piston and a pump chamber at the outer end of the piston, said explosion chamber being provided with a fuel inlet port and an exhaust port in its lateral walls, opened and closed by the moving piston, a transfer chamber adjacent to and communicating with the said fuel inlet port, the pump chamber having an outlet port adjacent to its outer end, a transfer passage connecting 110 said outlet port with the transfer chamber, means for admitting fuel to the transfer passage, said stationary piston being provided with an annular chamber, and an inlet port in its lateral wall, adjacent to its inner end communicating therewith and adapted to be opened and closed by the moving piston, a crank case provided with a 115

chamber separate from the interior of the crank case and having openings on its upper face adapted to register with apertures in the annular chambered portion of the stationary piston, said chambered portion of the crank case having an exterior inlet aperture communicating therewith.

In testimony whereof I affix my signature, in the presence of two witnesses.

ERNEST A. MEYER.
